(57) **CLAIM**

The ornamental design for a bottle, as shown and described.

DESCRIPTION

FIG. 1 is an elevation view showing our new design for a bottle at 45° rotation from the other elevation views;
 FIG. 2 is a back elevation view thereof;
 FIG. 3 is a right side elevation view thereof;
 FIG. 4 is a top plan view thereof;
 FIG. 5 is a bottom plan view thereof; and,
 FIG. 6 is a front elevation view thereof.

The broken lines are included for the purpose of illustrating the portions of the bottle that form no part of the claimed design.
